(57) **CLAIM**

The ornamental design for a catheter securement device as
shown and described.

DESCRIPTION

FIG. 1 is a top, front and left side perspective view of a
catheter securement device, in accordance with our new
design;

FIG. 2 is a right-side elevational view thereof; and,
FIG. 3 is a top plan view thereof.

The evenly-spaced broken lines in the figures depict portions
of the catheter securement device that form no part of the
claimed design. The dash-dot broken lines in the figures
depict peripheral boundaries of the claimed design and form
no part of the claimed design.

1 Claim, 3 Drawing Sheets
